DRILL PIPE CUTTER

Filed May 2, 1930

Fig. 1.

Inventor
Kearney Mitchell

By Adam E. Fisher.

Attorney

UNITED STATES PATENT OFFICE

KEARNEY MITCHELL, OF SULPHUR MINES, LOUISIANA

DRILL PIPE CUTTER

Application filed May 2, 1930. Serial No. 449,102.

This invention relates to improvements in drill pipe cutters and more particularly to a device for supporting a drill pipe while cutting the same for use in connection with the automatic drill pipe cutter which is the subject matter of my Patent Number 1,676,569 issued under date of July 10, 1928.

The object of the invention is to provide a simple and efficient device which may be readily attached to the aforesaid automatic drill pipe cutter in such manner that it will support the drill pipe being cut thus removing the weight of this pipe from the cutting mechanism of the cutter.

15 The foregoing and other objects together with means whereby the same may be carried into effect will best be understood from the following description of a preferred embodiment of the invention taken in connection with the accompanying drawings, wherein:

Figure 1 is a longitudinal sectional view of a drill pipe cutter equipped with the drill pipe supporting attachment.

25 Figure 2 is a plan view of the attachment alone.

Referring now more particularly to the drawings, 1 denotes a cylindrical shell connected by a coupling 2 to the operating pipe 15 which may be of any length and which is used for lowering the device into a well (not shown). A collar 4 is threaded in the upper end of the shell 1 and a coiled spring 5 is secured to the upper margin of this collar. A ring 6 is secured to the upper extremity of the spring 5 and lock prongs 7 are secured to this ring 6 as shown. The collar 4 has its inner wall beveled off conically toward its lower margin as shown so that when the collar is caused to move downward into the shell 1, as will be pointed out, the bits 9' of the cutter bars 9 will be forced inward into engagement with the drill pipe 12 to sever the same as the device is rotated about the pipe. The foregoing elements are shown and described in my aforementioned patent and no invention is claimed therefor in this application.

In carrying out the present invention a band or collar 20 is secured by rivets 21 in the lower end of the operating pipe 15, the

inner wall of this band 20 preferably, though not necessarily, being beveled conically outward from its top to its bottom towards the walls of the said pipe 15 as shown. A supporting ring 22 is then loosely mounted on top of the band 20 to turn thereupon, this ring 22 having equally spaced grooves 23 in its inner wall to receive the aforementioned lock prongs 7 which are sprung outwardly for this purpose. The said supporting ring 22 also has a plurality of equally spaced slots or recesses 24 in its upper, inner margin, which slots are disposed intermediate the aforesaid grooves 23. A plurality of supporting fingers or arms 25 are pivoted at one end by pins 26 in the slots 24 and these fingers are adapted to rest against the drill pipe 12 as shown under the influence of their own weight.

In use the device is lowered over the drill pipe 12, the supporting fingers 25 sliding freely along the pipe and over the joint 13 thereof. The device is then partially retracted causing the fingers 25 to engage the lower shoulder of the joint 13 anchoring the ring 22 so that when the operating pipe 15 is turned the said ring 22 will not turn but will remain stationary. Since the lock prongs 7 engage the slots 23 in the ring 22 the spring 5 and collar 4 will also be held against rotation causing the said collar to move downward in the shell 1 forcing the bits 9' inwardly. Upon continued rotation of the pipe 15 the drill pipe 12 will of course be cut off. It will be noted that by the use of the supporting ring 22 and arms 25 that the weight of the drill pipe being cut is not carried by the spring 5, collar 4 and cutter bars 9 as is the case when the lock prongs 7 engage the joint 13 to operate the cutter as shown in my prior patent but that the weight is supported upon the band 20.

While I have herein set forth a certain preferred embodiment of my invention, it is understood that I may vary from the same in minor details, not departing from the spirit of the invention and within the scope of the appended claims.

I claim:

1. In a device of the character described,

in combination with a drill pipe cutter including an operating pipe and lock prongs, a band secured in the operating pipe, a supporting ring rotatably mounted on the said band, means on the said supporting band to receive the said lock prongs, and supporting fingers pivoted to the said supporting ring.

2. In a device of the character described, 10 in combination with a drill pipe cutter including an operating pipe and lock prongs, a band secured in the operating pipe, a supporting ring rotatably mounted on the said band, the said supporting ring having grooves 15 in its inner wall to receive the said lock prongs, the said supporting ring also having a plurality of slots in its inner and upper margin, and a plurality of supporting fingers pivotally mounted in the said slots in the 20 supporting ring.

In testimony whereof I affix my signature.

KEARNEY MITCHELL.
